(57) **CLAIM**

The ornamental design for a chainsaw, as shown and described.

DESCRIPTION

FIG. 1 is a front and bottom perspective view of a chainsaw, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion labeled, 'FIG. 9' in FIG. 1; and,

FIG. 10 is an enlarged view of a portion labeled, 'FIG. 10' in FIG. 1.

The broken lines in the figures illustrate portions of the chainsaw that form no part of the claimed design. The dot-dash broken line circles depict the limits of the enlarged views and form no part of the claimed design. The dot-dash lead lines in FIG. 1 labeled FIGS. 9 and 10 indicate the areas from which the enlargements in FIGS. 9 and 10 are taken and form no part of the claimed design.
